BELT UNLOADING MECHANISM

Arthur R. Young, Detroit, Mich.

Application August 24, 1948, Serial No. 45,876

8 Claims. (Cl. 198—188)

1

This invention relates to apparatus for controlling delivery of material from an endless conveyer to a series of bins or hoppers.

An important object of the present invention is to provide an apparatus of the above-mentioned character that is automatic in its operation to control flow of material into the hoppers.

Another object of the invention is to provide an apparatus of the above-mentioned character that assures a more uniform distribution of material to the hoppers.

Still another object of the invention is to provide an apparatus of the above-mentioned character that is automatically operative to regulate the amount of material delivered to each of the hoppers.

Yet another object of the invention is to provide an apparatus of the above-mentioned character that materially reduces loss of material over the head of the conveyer.

A further object of the invention is to provide an apparatus of the aforementioned character that effects a saving in time and labor as compared with conventional apparatuses now in use.

A still further object of the invention is to provide an apparatus of the above-mentioned character that is simple and rugged in construction and that can be installed and maintained relatively inexpensively.

Other objects and advantages of the invention will be apparent during the course of the following description.

In the drawing forming a part of this specification and wherein like numerals are employed to designate like parts throughout the same,

Fig. 1 is a top plan view showing apparatus embodying the present invention associated with the belt conveyer and one of the hoppers for receiving material from the conveyer, and

Fig. 2 is a vertical sectional view taken on the line 2—2 of Fig. 1.

The present invention is primarily adapted and preeminently suited for use in foundries. It is not limited to such use, however, and can be used in any capacity where apparatus of this character has utility.

In conventional foundry practice, tempered sand is delivered to a row of overhead hoppers by a belt conveyer. This sand is taken from the hoppers as required and spouted into molds on molding machines located adjacent to the hoppers. Finished molds are then taken from the molding machines and placed on the pouring lines.

Since large amounts of sand are used in this

2

manner, it must be delivered at regular intervals to the hoppers. Usually, sand is delivered to the row of hoppers more or less continuously by a suitable conveyer and sand is diverted into the respective hoppers as required by plows which are moved manually to and from the surface of the conveyer belt.

In at least one type of conventional installation, the conveyer belt passes directly over the hoppers and V-shaped plows associated with the hoppers are disposed above the belt. The plows are pivotally mounted so that they can be lowered to a position on the belt or raised to a position above the belt. When the plows are lowered they scrape sand from the conveyer belt into their respective hoppers; and when the plows are raised, sand on the belt merely passes over the hoppers without interference from the plows.

The system particularly described above requires the constant attention of a workman who operates the plows manually to keep the hoppers supplied with sand. Labor costs are high, and this procedure is therefore expensive. Moreover, the procedure is wasteful both of man power and sand, since constant vigilance is necessary to keep all of the hoppers properly and generally uniformly filled. Even then a considerable amount of sand is not diverted into the hoppers but passes over the head of the conveyer. This sand must then be collected and reconditioned for re-use. The result is inefficiency and increased cost of operation. In addition to the above, this system is haphazard in operation and does not assure uniform distribution of sand to the hoppers or proper regulation of the amount delivered to any particular hopper.

In the drawing I have shown, by way of illustration, a preferred embodiment of apparatus for performing the above operations automatically. According to the present invention, a hopper 10 is disposed beside an endless belt conveyer 12 and the latter is supported on a horizontal platform 14 which extends from the inner side of the hopper. The platform 14 provides a flat unyielding surface for supporting the belt 12 as it passes the bin 10. The end walls 16 and 18 of the hopper 10 extend substantially above the belt 12 and the inner edges of the extending wall portions preferably overlie the adjacent inner marginal edge 50 of the belt, as shown in Fig. 2.

Suitably wetted or tempered molding sand is delivered onto the conveyer belt 12 in any suitable or conventional manner and is carried along by the belt in the direction of the arrow in Fig. 1. It is to be understood that the belt 12 con-

veniently may deliver sand to a row of hoppers 10 in the manner hereinabove suggested. Thus, while only one hopper 10 is here shown, it is contemplated that any desired or necessary number of hoppers may be arranged beside the conveyer belt 12. According to the present invention, each of the hoppers 10 is equipped with an automatically operable plow for diverting sand as required from the belt 12 into the hopper. Each of these plows is identical in construction and operation and a detailed description of one therefore will suffice.

Essentially, the automatic plow of this invention comprises a row of blades 20, 22, 24 and 26 arranged in a diagonal line from edge to edge of the conveyer belt 12 and with the ends thereof in overlapping relation so as to deliver material at one edge of the belt and into the hopper 10. The blades 20, 22, 24 and 26 are carried by arms 28, 30, 32 and 34 respectively, which arms are mounted on a common pivot rod 36 carried by the end walls 16 and 18. Each of the arms 28-34 can be rocked on the pivot 36 to move its respective blade to and from the conveyer belt 12. In practice the arms 28-34 are actuated by a pivoted vane 38 located in hopper 10 adjacent the outer wall thereof and mounted to swing on pivots 40 and 42 which are journaled in the end walls 16 and 18. Adjustable set screws 44, 46, 48 and 50 carried by and movable with the vane 38 engage respective arms 28, 30, 32 and 34 at the right of pivot rod 36 as viewed in the drawing. The screws 44-50 are independently adjustable so that they can be set to engage their respective arms 28-34 at different predetermined times as the vane 38 swings on its pivots and across the hopper 10.

Specifically, the blades 20-26 conveniently can be made of sheet metal, and they preferably are generally rectangular in form as shown in the drawing. Each blade is fastened to its respective arm by a pivot 52. In the form of the invention here shown by way of illustration, the arms 28-34 are in the form of angle irons. The pivots 52 are fastened to their respective blades 20-26 by lugs 54, and each pivot extends through and is supported by one flange of its respective supporting arm. At the outer ends thereof the arms 28-34 are formed with depending portions 56 which extend downwardly behind the blades 20-26 and limit outward swinging movement of the blades 20-26. As a result of this construction, the blades 20-26 can swing inwardly for limited distances to accommodate any downward movement of the supporting arms which may occur after the blades engage the belt 12. At the same time, the depending portions 56 form rigid back-up members for the blades 20-26 which prevent the sand or other material on the conveyer belt 12 from pushing against and passing under the blades.

The vane 38 also is generally rectangular in form as perhaps best shown in Fig. 1, and it is sufficiently large so that it substantially fills the entire cross section of the hopper when in the angular or diagonal position shown by full lines in Fig. 2. Vane 38 conveniently can be made of sheet metal.

Any suitable means may be provided for cooperatively associating the vane 38 and adjusting screws 44. In the form of the invention here shown, an angle iron 58 extends along and is welded or otherwise attached to the upper marginal edge of the vane 38. Transverse supporting angles 60, 62, 64 and 66 are fastened to the

angle 58. The supports 60, 62, 64 and 66 correspond in number to the arms 28-34 and each support is disposed in alignment with a respective one of the arms. Adjusting screws 44-50 are carried by respective supports 60-66, and each screw preferably is provided with a lock nut 68 which holds it in selected adjusted position. As best shown in Fig. 2, the adjusting screws 44-50 project from the supports 60-66 and engage their respective supporting arms 28-34 in such manner that movement of the vane 38 is necessarily co-ordinated with movement of the blades 20-26 and vice versa.

When material in the hopper 10 is approximately at the level or below the lower edge or vane 38 there is little or no resistance to pivotal movement of the vane. Consequently, the weight of blades 20-26 acting through the supporting arms 28-34 and adjusting screws 44-50 will swing the vane 38 to the left to the full-line position shown in Fig. 2. When the blades 20-26 are thus positioned, they collectively form a barrier for material on the belt 12, and as the belt moves in the direction of the arrow in Fig. 1, the blades divert material on the belt laterally into the hopper 10. Manifestly, all of the sand or other material on the belt 12 will be swept off by the blades 20-26 as long as all of them are in contact with the belt.

Material delivered to the hopper 10 falls downwardly through the elongated slot or space between the inner side of the hopper and the lower edge of the vane 38. Consequently, in use there will be a peak height of the material directly under this slot, and the material will slope away from the peak toward the outer side of the hopper 10. Thus the material in the hopper does not interfere with swinging movement of the vane 38 from the full line back into the hopper to substantially the dotted-line position. As soon as the level of material in the hopper 10 reaches the lower edge of the vane 38 it will begin to pile up against the vane, and the weight of material against the vane forces the latter to swing to the right as indicated by the arrow in Fig. 2. As the vane 38 swings in this direction, it reacts through screws 44-50 and arms 28-34 to raise the blades 20-26.

Adjusting screws 44-50 can be set so that the blades 20-26 are raised from the belt 12 simultaneously or in any predetermined sequence or order. Where there are a large number of hoppers to be filled, important advantages in operation are obtained if the blades are raised sequentially one after the other from the belt 12. Usually, it will be desirable first to lift the outermost blade 20 and then to lift the other blades one after the other as the hopper fills. Thus the adjusting screw 44 is set so that it will lift the blade 20 almost immediately when the vane 38 begins to swing to the outside of the hopper. After the blade 20 has raised slightly from the belt 12, adjusting screw 46 engages arm 30 to raise the blade 22. Shortly after the blade 22 has been raised from the belt 12, adjusting screw 48 engages supporting arm 32 to raise the blade 24. Finally, after all of the other blades have been raised from the belt 12, adjusting screw 50 engages supporting arm 34 to raise the blade 26.

In this manner, some sand is permitted to go through the plow to other hoppers as soon as the first blade 20 is raised and this will occur as soon as the hopper 10 is filled to a point where the vane 38 begins to swing to the right. The sand which goes through the plow will be that portion of the sand which would normally be diverted by

the blade 20. As soon as blade 20 is raised from the belt, the sand which is diverted goes on past the hopper 10 to the next adjacent hopper in the series where it is collected and swept into the latter hopper by the plow associated therewith. As the hopper 10 continues to be filled, the blades are raised progressively and sequentially from the belt 12 and proportionately greater amounts of sand are permitted to pass through the plow to the adjacent hopper.

From the foregoing, it will be readily apparent that if sand is delivered to the hopper 10 faster than it is withdrawn, it eventually will be filled to a point where all of the blades 20-26 are raised from the belt 12. As the blades rise, one after the other, progressively greater amounts of sand pass to the adjacent hopper or hoppers. When all four are raised, all the sand is permitted to pass without interference.

On the other hand, if sand is drawn rapidly from a hopper after one, two, or three of the blades have been raised so that the sand is no longer being supplied to the hopper at a rate sufficiently to overcome or compensate for withdrawal, the level of sand in the hopper will drop and the weight of the raised blade or blades will force the vane 38 back to the left. As the vane 38 moves in this direction, the blades drop progressively onto the belt 12 and progressively increasing amounts of the sand are again delivered to the hopper 10.

If the hopper 10 is full so that the blades 20-26 are elevated from the conveyer belt 12 and only small amounts of sand are taken from the hopper, the amount taken may be compensated by less than all of the blades. As soon as the level of sand in the hopper 10 falls to a point where the first blade 20 is dropped onto the belt 12, some sand will be diverted from the conveyer into the hopper and this alone may be sufficient to fill the hopper to a point where the blade 20 is again raised from the conveyer belt. On the other hand, if a greater amount of sand is required to compensate for the amount withdrawn from the hopper 10, it may be necessary to lower two, three, or even four of the blades onto the conveyer belt 12. This is done automatically in the manner suggested.

In view of the foregoing it will be readily apparent that I have achieved the object of the invention. Sand is delivered to the hopper directly according to the rate of withdrawal, and all of the operations which control delivery of material to the hopper are entirely automatic. By properly adjusting the screws 44-50, a desired level of sand may be maintained in the hopper. By reason of this arrangement, sand is taken off the conveyer automatically as it is needed; and if an adequate supply of sand is maintained on the conveyor, none of the hoppers supplied by the conveyer need ever be empty. A uniform distribution of sand to the several hoppers is obtained and the amount of sand delivered to any particular hopper can be easily regulated. Since the entire operation is automatic, there is a substantial saving in time and labor which previously was required. The construction of the apparatus is simple and rugged, thus assuring low cost both in installation and in maintenance.

Having thus described the invention, I claim:

1. A multiple blade automatic plow for delivering sand or the like from an endless conveyer belt to a hopper at one side of the belt comprising a plurality of plow blades arranged diagonally across the conveyer belt with the individual blades disposed in overlapping relation; a pivoted

supporting arm for each of said blades; a pivoted vane in said hopper; and actuators carried by and movable with the vane and engaging said arms, said actuators operable by pivotal movement of the vane in one direction to raise the blades from the conveyer belt and operable by pivotal movement of the vane in the opposite direction to lower the blades onto the conveyer belt.

10 2. The combination as set forth in claim 1 wherein said actuators are individually adjustable to engage and release their respective arms sequentially upon pivotal movement of said vane.

3. A multiple blade automatic plow for delivering sand or the like from an endless conveyer belt to a hopper at one side of the conveyer belt comprising a vane mounted in the hopper for swinging movement about a generally horizontal axis; a plurality of individually adjustable set screws carried by the vane; a plurality of pivoted arms disposed above the conveyer belt, each arm being engaged by a respective one of said set screws and adapted to be rocked about its pivot by swinging movement of the vane; and 25 a plurality of generally upright blades each carried by a respective one of said arms, said blades arranged diagonally across the conveyer belt and disposed in overlapping relation with respect to each other, said blades being individually 30 actuatable relative to the conveyer belt by said vane acting through said arms and said set screws being adjustable to move the blades in predetermined sequence.

4. A multiple blade automatic plow for delivering 35 granular material from an endless conveyer belt to a hopper comprising a plurality of pivoted arms disposed about the conveyer belt; generally upright blades each carried by a respective one of said arms, said blades arranged diagonally 40 across the conveyer belt from edge to edge thereof and disposed in overlapping relation with respect to each other; a vane mounted in the hopper for swinging movement about a generally horizontal axis; and means operable by said vane 45 and engageable with said arms to move the blades relative to the conveyer belt.

5. A multiple blade automatic plow for delivering granular material from an endless conveyer belt to a hopper disposed beside the belt comprising 50 a plurality of generally upright, individually movable blades above the conveyer belt; a pivoted carrier for each of said blades; and control means for actuating said pivoted carriers to move said blades to and from said belt, said 55 control means being responsive to the level of material in the hopper and operative to move the blades in predetermined sequential order onto the belt as the level of material in the hopper drops and to raise the blades from the conveyer belt in reverse order as the level of material in the hopper rises.

6. The combination as set forth in claim 5 wherein the control means is pivotally mounted in the hopper at the side thereof remote from 60 said conveyer belt.

7. The combination as set forth in claim 5 wherein said control means comprises a generally upright pivoted vane in said hopper, and adjustable means carried by and movable with said vane for actuating said carriers.

8. The combination as set forth in claim 5 wherein said control means comprises a pivoted vane mounted in the hopper at the side thereof remote from said conveyer belt, and a plurality 75 of adjustable means carried by and movable with

said vane, said adjustable means engaging respective carriers and operable by movement of the vane about its pivot to actuate said carriers in predetermined sequence.
